ORIENTING CORE BARREL

Cecil Howard Sweet, Huntington Park, and
Lawrence Shiner Chambers, Los Angeles, Calif.

Application June 11, 1937, Serial No. 147,704

5 Claims. (Cl. 255—72)

This invention relates to an orienting core barrel. The prime object of which is to enable the operator to determine the strike or direction of the formation from which the core is taken.

An object of our invention is to provide a novel orienting core barrel in which a mark on the formation is aligned with a survey instrument in such a manner that the picture taken by the survey instrument will impart knowledge to the operator, relative to the strike or direction of the formation.

Still another object is to provide a novel orienting core barrel of the character stated in which the survey instrument is always positioned in a known relation to a marker arranged at the lower end of the core barrel.

Still another object is to provide a core barrel of the character stated in which a survey instrument is lowered into the barrel, after the barrel has been run into a well, thereafter taking a picture with the survey instrument, said picture giving information relative to the strike or direction of the formation. Thereafter raising the survey instrument to the surface and then continuing the coring operation with the core barrel.

A feature of our invention resides in the ability to use a standard core barrel and to arrange in that barrel a punching block and super-imposing on the barrel, a receiver for the survey instrument and thus orient the core which is recovered in the standard or usual core barrel.

Other objects, advantages and features of invention may appear from the accompanying drawings, the subjoined detailed description and the appended claims.

In the drawings—

Figure 1 is a diagrammatic longitudinal sectional view of our orienting core barrel.

Figure 2 is a fragmentary longitudinal sectional view of the upper portion of the core barrel.

Figure 3 is a fragmentary longitudinal sectional view of the lower part of the core barrel.

Figure 4 is a longitudinal sectional view of the non-magnetic sleeve showing the survey instrument in side elevation.

Figure 5 is a fragmentary longitudinal sectional view of the lower part of a punch core barrel.

Figure 6 is a fragmentary longitudinal sectional view of still another type of punch core barrel.

Referring more particularly to the drawings, the numeral 1 indicates a core barrel of usual and well known construction. The core barrel carries the usual core head or cutter 2. Within the core head, there is provided the usual core

catcher or fingers 3. A plug 4 is mounted in the head 2 and this plug is provided with an annular shoulder 5 at the upper end, to be engaged by the fingers 3. The plug is held in position at the core head 2 by means of a plurality of shear pins 6. A core marking pin 7 extends into a bore 8 in the bottom of the plug 4. The pin is held in position by a shear pin 9 and a coil spring 10 bears against the top of the pin for the purpose of urging the pin outwardly as will be further described. The pin 7 has a peculiar shape or conformation, for example, it might be flat on one side. A second coil spring 11 encircles the pin 7 and extends slightly below the tip of this pin. When the core barrel is dropped or "spudded" in the formation, the pin 9 is first sheared, whereupon the spring 10 presses the pin downwardly so that it remains in the formation. The spring 11 is compressed. The pins 6 are sheared off as additional weight is exerted, and when these pins shear, the recoil of the spring 11 will throw the plug 4 upwardly into the core barrel 1, thus leaving the barrel free to receive the core as the barrel is subsequently rotated to recover a sample of the formation. To the upper end of the barrel 1, we attach a pipe section 12 and the drill pipe is attached to the upper end of the pipe 12 by the usual joint or coupling 13. A non-magnetic sleeve 14 is fixedly secured within the pipe section 12. A means of securing the sleeve might be an annular nut 15 which screws into the pipe and against a shoulder 16 on the sleeve. The sleeve is provided with a longitudinal slot or groove 17 and the upper end is tapered as shown at 18 for the purpose of guiding the survey instrument as will be further described.

A survey instrument 19, preferably of any well known "single shot" type, is lowered into the drill pipe on a cable 20. A lug or roller 21 projects from the shell of the survey instrument and as the instrument is lowered into the well, this roller engages the tapered surface 18 and is guided into the slot 17. This slot 17 is arranged in a fixed and known position, relative to the pin 7. For example, the slot can be aligned with the flat side of the pin. When the survey instrument is in position, as shown in Figure 2, it will then be in a known position relative to the pin 7. The survey instrument 19 contains a compass which is photographed as the instrument comes to rest within our core barrel. The compass, as well as the photographic mechanism, is not shown since it is usual and well known. The operation of the barrel previously described is as follows:

The barrel is lowered into the well on the drill pipe in the usual and well known manner. When bottom is reached, the barrel is raised above the bottom of the hole, a distance of several feet. 5 Circulation is then established and the bottom of the hole is well washed. The survey instrument is then lowered into the well to its resting place in the core barrel. The barrel is then spudded downwardly so that the pin 7 will penetrate the formation. 10 The tool is allowed to remain in this position until the timing mechanism of the survey instrument has operated and a picture is taken of the compass. The survey instrument is then withdrawn from the hole and the coring operation continues in the usual and well known manner. After the core has been taken, it is raised to the surface. The pin 7 either remains in the top of the core or the peculiar imprint of the pin 15 will be evident in the top of the core. From the developed picture in the survey instrument, which can be aligned with the roller 21 simply by marking the survey instrument in the usual and well known manner, it is possible to place the core and the picture from the survey instrument in exactly the position they occupied when the core barrel was first spudded down. Thus, the exact strike or position geographically that it occupied in its natural state, will be shown, thereby 20 permitting the operator to observe carefully and accurately the angle of inclination and the magnetic bearing of the axis or plane of the formation. 25

It is obvious that the survey instrument may also include an inclinometer for the purpose of determining the inclination at the bottom of the hole, so that the core can be straightened when on the surface to accurately conform to its position when in its natural state. 30

40 In Figures 5 and 6, we have illustrated a punch core type of barrel in which a sub 22 is attached to the lower end of the pipe section 12. A punch core barrel 23 is secured to the lower end of the sub 22. The sub is provided with a central fluid passage 24 and with fluid outlets 25 at the lower end. The barrel 23 is provided with a marker 26, either on the inside or outside of the barrel and preferably the outside as shown. This marker may consist of a single rib or the like 45 and this rib is aligned or arranged in a known position relative to the slot 17 in the non-magnetic sleeve 14. Relief ports 27 are provided at the upper end of the barrel 23.

50 In Figure 6 the punch core barrel 28 is attached to the plug 29 which fits into the lower end of the usual core barrel. The plug 29 is held in position by the balls 30 which normally rest in indentations in the wall of the core barrel shoe 31. After the core is taken in the barrel 28, rotation of the shoe 31 will retract the balls 30 and thereafter the plug 29 and the barrel 28 can slide upwardly into the standard core barrel 55 above the shoe 31, so that a regular core can be taken after the punch core sample has been recovered. The barrel 28 is provided with relief ports 32 at the upper end thereof so that a full core can be taken therein.

60 In operation, the tool is lowered into the well together with the survey instrument 19. The tool is spudded down and a punch core is taken. While the tool is in this position, the time mechanism in the survey instrument takes its picture. The entire tool is then returned to the surface and the sample recovered in the punch core 65 barrel and arranged in known relation to each

other and thus the strike or axis of the cored formation can be determined.

When a standard core barrel is then run into the hole and the regular core taken, the mark made by the punch core barrel will be apparent 5 in the core and again the regular core can be compared with the picture of the survey instrument to determine its strike.

In the modification shown in Figure 6, the punch core is first taken and the regular core 10 is next taken without having to remove the instrument from the well. The method of aligning the punch core with the survey instrument is the same as previously described.

Having described our invention, we claim: 15

1. In an orienting core barrel, a pipe section at the upper end of the core barrel adapted to receive a survey instrument lowered from the surface on a line, aligning means in the pipe section engageable by the survey instrument whereby the survey instrument is positioned in a known position in the core barrel and core marking means on the core barrel and means releasably holding the core marking means in the lower end of the core barrel, said core marking means being adapted and arranged to move upwardly into the core barrel when released, and a spring on the lower end of the core marking means compressed by contact with the top of the uncut core to cause said upward movement of the core marking means in a sudden manner when the releasable means is released. 20

2. In an orienting core barrel, a pipe section arranged at the upper end of the core barrel, said pipe section being adapted and arranged to receive a survey instrument lowered from the surface on a line, mounting means in the pipe section to receive the survey instrument and core marking means on the lower end of the core barrel, aligning means in the pipe section engageable by the survey instrument whereby the survey instrument is always arranged in known position in the pipe section, said aligning means being arranged in known position to said core marking means, and means releasably holding the core marking means in the lower end of the core barrel, said core marking means being adapted and arranged to move upwardly into the core barrel when released, and a spring on the lower end of the core marking means compressed by contact with the top of the uncut core to cause said upward movement of the core marking means in a sudden manner when the releasable means is released. 40

3. In an orienting core barrel including a core receiving barrel, a pipe section mounted on the upper end of the barrel, a sleeve mounted within the pipe section, said sleeve being adapted and arranged to receive a survey instrument, aligning means in the sleeve engageable by the survey instrument, a plug positioned in the lower end of the core barrel, means releasably engaging the plug and core marking means carried by the plug, said releasable means engaging the plug including shear pins extending from the barrel into the plug, and a spring on the lower end of the plug compressed by contact with the top of the uncut core to cause sudden upward movement of the plug when said pins shear. 55

4. In an orienting core barrel, a pipe section at the upper end of the core barrel adapted to receive a survey instrument lowered from the surface on a line, aligning means in the pipe section engageable by the survey instrument whereby the survey instrument is positioned in a 70

known position in the core barrel, a plug releasably mounted in the lower end of the core barrel, said plug projecting below the core barrel, core marking means carried by the plug and shear pins extending into the plug, said pins, when sheared, releasing the plug for upward movement into the core barrel, and a spring on the lower end of the plug compressed by contact with the top of the uncut core to cause said upward movement of the plug in a sudden manner when said pins shear.

5. In an orienting core barrel, a plug mounted

in the lower end of the core barrel, said plug extending below the core barrel, shear pins extending into the plug, said pins, when sheared, permitting upward movement of the plug into the core barrel, and a spring on the lower end of the plug compressed by contact with the top of the uncut core to cause said upward movement of the plug in a sudden manner when said pins shear.
